INVENTOR

United States Patent Office.

LEWIS F. BETTS, OF CHICAGO, ILLINOIS.

Letters Patent No. 81,584, dated September 1, 1868; antedated August 20, 1868.

IMPROVEMENT IN LANTERNS.

The Schedule referred to in these Letters Patent and making part of the same.

TO ALL WHOM IT MAY CONCERN:

Be it known that I, LEWIS F. BETTS, of the city of Chicago, in the county of Cook, and State of Illinois, have invented certain new and useful Improvements in Lanterns; and I do hereby declare that the following is a full, clear, and exact description of the same, reference being had to the accompanying drawings, making a part of this specification, in which—

Figure 1 represents a lantern with a vertical fourth removed.

Figure 2, a horizontal semi-section at the lower guard-ring.

Figure 3 represents the mode of attaching the guard to the base and the spring-stop of the guard, and

Figure 4 the fastening for securing the wires of the guard at the intersections.

Like letters refer to the same parts in all of the figures.

The nature of my invention consists in securing the upper end of the globe in the top or cap of a lantern by a series of springs or a spring-band, pressing against the side of the globe at such upper end; in constructing the main portion of the base in sections, and fastening them together by means of flanches; in fastening the flanches by eyelets; in supporting the guard of the lantern upon ledges or brackets at the base of the guard, so as to leave an open space between the lower guard-ring and the base of the lantern; in a novel mode of attaching a removable guard to a lantern; in a new and improved fastening for the wires of the guard at their intersections, and in securing the lamp or oil-pot to the base by means of inclined edges or cones.

To enable others skilled in the art to make and use my invention, I will proceed to describe my improved lantern.

The flange, E, of the base is made of the ordinary size, and is carried into the lantern beyond the vertical portion of the base to the oil-cup. Two holes, g, are cut on opposite sides, and a portion of the metal turned or stamped up, so as to form the cams or inclines b, hereinafter more fully described. The vertical portion, D, of the base I usually make in three sections, although it can be made in two or more than three. These sections are cut in the proper form and stamped, so that the middle will be of the proper curve of the lantern, and a flanche, F, formed at each end of each section. Near the middle of each section, at the lower edge, I leave a small point of the metal i to project through the base-flange E. I fasten the flanches F together by the eyelets d, and then pass the points i through the base-flange E, and bend them down, so as to hold the whole base together without solder. The wire or ring J is inserted before the flanches are fastened together. I then dip the whole base into molten solder, which solders the flanches F together, and also solders firmly the base-flange E and the ring J, so that I am enabled to construct them with great rapidity.

The oil-pot or lamp G is made in the form shown, or in any convenient form, and has a rod or wire passing through it, at the proper point to form the lugs or pins c. In inserting the lamp, the pins c pass through the openings g, when the lamp is turned on the inclines or cams b, as far as is necessary to make the bottom of the lamp fit closely and firmly against the flange or band to which the cams are attached. I usually make these cams or inclines with a slight rise, commencing at one spring, g, and continuing to the other one on the opposite side. If, however, the angle of the incline is increased, it will not need to be carried as far on the raised or projecting edge, but by making the angle slight there is no tendency in the lamp to turn on the inclines and drop out. The guard at the top is permanently attached to the band or projection L, and at the lower end the vertical rods or wires are secured to a band or ring, I, by means of a peculiar fastening, f, and the alternate rods N extend below the ring or hoop I, so as to form hooks, e, (shown more fully at fig. 3,) which project down, and by a slight turn of the guard are made to enter the holes d in the ledge or brackets formed by the union of the flanches F, and when made by the union of the flanches, as described, the holes d are the eyelet-holes mentioned, but it will be obvious that, for the purpose of attaching the guard to the base, brackets or ledges attached to a band made of a single piece can be used as well.

The lower band or ring rests on the outer extremity of the brackets in the notches, or against the shoulders h, where it is securely held by the hooks e.

The guard is prevented from becoming detached by the spring K attached to the rod or band J, (figs. 2 and 3.) This spring presses against the rod or wire N, and also against the guard-ring I, so that it is impossible to detach the guard without depressing the spring by hand, and when so depressed a slight turn will detach it. The guard-ring H is secured to the rods N by the same fastener as that used for ring or band I. If, however, a stamped band is used at I, rods N can then pass through such band, and be soldered.

By the use of the fastener f in the construction of the guard, I am enabled to complete it without the use of solder, for by the use of pliers constructed for that purpose, the pieces p are thoroughly clamped on, so that when put together I can dip the guard in molten solder, as described, for the base, and thoroughly solder every joint and intersection, and make the guard doubly strong, and in less time than is consumed by any mode of fastening guard-rods heretofore known or used.

The globe or glass rests upon the band D, as shown, and its upper end is kept in position firmly by the band C. This band is cut, as shown at a, at short intervals, so that the parts of the band will operate as springs, and not only keep the globe in place and prevent rattling, but will accommodate themselves to different-sized globes and always make a perfect fit. Perfect springs can be used in place of this band, but not so cheaply, and it will be obvious that this band or these springs can be placed so as to fit either the inside or outside of the upper end of the globe, but I prefer the outside, as shown.

This band C can be made of the lower portion of the cap or dome A, or of a separate piece soldered on, as may be most convenient. The cap or dome A is provided with the usual bail, M, and is made of any desired configuration, as may be also the base, D; thus, when completed, making a strong, durable, cheap, and complete lantern, and by only interposing the ring J, one which will not obscure the light for a great distance around and below it.

Having thus fully described my lantern, what I claim as new, and desire to secure by Letters Patent, is—

1. The spring-band C, for securing the upper end of the globe, substantially as specified.
2. Constructing a lantern-base of two or more sections, D, provided with flanches F, substantially as and for the purposes set forth.
3. Securing the flanches and forming the carrying-holes for the guard, by means of eyelets at d, substantially as described.
4. The brackets or ledges F, for supporting and carrying the guard at a distance from the main portions of the base, substantially as specified.
5. The rod or ring J, for strengthening the base and supporting the brackets or ledges without materially obstructing the light, substantially as specified.
6. The extended guard-rods N, when such extended portion e is used for a hook or catch, substantially as described.
7. The combination and arrangement of the guard, provided with hooks e with the brackets F, substantially as and for the purposes specified.
8. The spring-stop K, in combination with the hooks e and bracket F, for preventing the detachment of the guard, substantially as specified.
9. The inclines or cams b, for securing and tightening the lamp, in combination with the pins c, substantially as specified.
